CLAIM

The ornamental design for a landscape lighting fixture housing, as shown and described.

DESCRIPTION

FIG. 1 is a perspective view of the top, left side, and front of a first embodiment of a landscape lighting fixture housing incorporating the design of my invention;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a rear elevational view thereof;

FIG. 8 is a perspective view of the top, left side and front of a second embodiment of a landscape lighting fixture housing incorporating the design of my invention;

FIG. 9 is a front elevational view thereof;

FIG. 10 is a left side elevational view thereof;

FIG. 11 is a right side elevational view thereof;

FIG. 12 is a top plan view thereof;

FIG. 13 is a bottom plan thereof; and,

FIG. 14 is a rear elevational view thereof.
